(57) **CLAIM**

The ornamental design for a shoe upper, as shown and described.

DESCRIPTION

FIG. 1 is a perspective view of a first embodiment of a shoe upper showing my new design;

FIG. 2 is a front elevational view of the shoe upper of FIG. 1;

FIG. 3 is a back elevational view of the shoe upper of FIG. 1;

FIG. 4 is a right side elevational view of the shoe upper of FIG. 1;

FIG. 5 is a left side elevational view of the shoe upper of FIG. 1;

FIG. 6 is a top plan view of the shoe upper of FIG. 1;

FIG. 7 is a bottom plan view of the shoe upper of FIG. 1;

FIG. 8 is a perspective view of a second embodiment of a shoe upper showing my new design;

FIG. 9 is a front elevational view of the shoe upper of FIG. 8;

FIG. 10 is a back elevational view of the shoe upper of FIG. 8;

FIG. 11 is a right side elevational view of the shoe upper of FIG. 8;

FIG. 12 is a left side elevational view of the shoe upper of FIG. 8;

FIG. 13 is a top plan view of the shoe upper of FIG. 8;

FIG. 14 is a bottom plan view of the shoe upper of FIG. 8;

FIG. 15 is a perspective view of a third embodiment of a shoe upper showing my new design;

FIG. 16 is a front elevational view of the shoe upper of FIG. 15;

FIG. 17 is a back elevational view of the shoe upper of FIG. 15;

FIG. 18 is a right side elevational view of the shoe upper of FIG. 15;

FIG. 19 is a left side elevational view of the shoe upper of FIG. 15;

FIG. 20 is a top plan view of the shoe upper of FIG. 15;

FIG. 21 is a bottom plan view of the shoe upper of FIG. 15;

FIG. 22 is a perspective view of a fourth embodiment of a shoe upper showing my new design;

FIG. 23 is a front elevational view of the shoe upper of FIG. 22;

FIG. 24 is a back elevational view of the shoe upper of FIG. 22;

FIG. 25 is a right side elevational view of the shoe upper of FIG. 22;

FIG. 26 is a left side elevational view of the shoe upper of FIG. 22;

FIG. 27 is a top plan view of the shoe upper of FIG. 22; and,

FIG. 28 is a bottom plan view of the shoe upper of FIG. 22.

(Continued)

The broken lines shown on the shoe upper in FIGS. 1-28 are for illustrative purposes only and form no part of the claimed design.
